CLAIM

The ornamental design for a frame for built-in home appliances, as shown and described.

DESCRIPTION

1. Frame for built-in home appliances

1.1 : Perspective

1.2 : Front

1.3 : Back

1.4 : Left

1.5 : Top

1.6 : Bottom

1.7 : Reference view

1.8 : Reference view 2

Reproduction 1.1 is a front perspective view of the frame for built-in home appliances; reproduction 1.2 is a front view thereof; reproduction 1.3 is a back view thereof; reproduction 1.4 is a left view thereof where the right view is a mirror image; reproduction 1.5 is a top view thereof; reproduction 1.6 is a bottom view thereof; reproduction 1.7 is a reference view showing the state where various modularized built-in home appliances are installed inside, and forms no part of the claimed design; reproduction 1.8 is a reference view showing the state where the cover is attached to the front, and forms no part of the claimed design; this design is for a frame for built-in home appliances in which various modularized built-in home appliances (such as a television receiver, hub for home network, hub for IoT, speaker, air purifier, etc.) can be installed, as shown in reproduction 1.7;

(Continued)

as shown in reproduction 1.8, the design is used inside such as in a living room, once the cover is attached to the front.
